UNITED STATES PATENT OFFICE

BOLDEN S. KELLEY, OF CROCKETT, TEXAS

LINE RACK FOR CULTIVATORS

Application filed September 7, 1928. Serial No. 304,579.

This invention relates to new and useful improvements in line racks for horse drawn cultivators and aims to provide novel, simple and useful racks to which the draft animal 5 reins or lines are arranged to enable the driver of the implement to maintain the lines in straight condition and also to prevent the lines from becoming tangled in the machine.

Furthermore the rack serves as a means 10 for supporting the weight of the major portion of the line and will prevent the lines from dropping to the ground throughout their entire length. Another important feature of the invention is the provision of a 15 rack of this character that may be rapidly secured to the draw beam or tongue of a conventional cultivator without in any manner altering the construction of the cultivator.

20 With the foregoing and other objects in view as the nature of the invention will be better understood, the same comprises the novel form, combination and arrangement of parts hereinafter more fully described, shown 25 in the accompanying drawings and claimed.

In the drawing wherein like reference characters indicate corresponding parts throughout the several views:

Figure 1 is a fragmentary side elevation 30 of a generally conventional cultivator equipped with my improved line rack,

Figure 2 is a vertical section through the cultivator draw beam or tongue on a somewhat enlarged scale looking rearwardly toward the 35 line rack for disclosing the line rack in side elevation and

Figure 3 is an enlarged vertical section through one of the line receiving units of the rack taken substantially upon the line 3-3 40 of Figure 2.

Now having particular reference to the drawings A designates generally a conventional cultivator but among other structural elements includes a forwardly extending 45 draw beam or tongue B. My invention consists of a pair of spaced parallel metallic straps 5-5 preferably of integral structure and being formed from a single length of metallic strapping bent over intermediate its 50 ends as clearly illustrated in Figure 2. These

straps 5-5 are provided with a series of registering openings 6 and are adapted for disposition upon opposite sides of the draw beam or tongue B after which bolts 7-7 are arranged through registering openings at opposite sides of the beam to rigidly secure the said straps to said beam. 55

Arranged upon the upper end of the single unit attaching member is a horizontal cross strap 8, the opposite ends of which are so 60 bent as to provide vertically extending elongated rein guides 9-9, these guides being opened at their inner sides and at their upper ends as clearly illustrated in Figure 2.

The material forming these guides at the 65 bottom of the openings therein is so formed as to provide shoulders 10-10 while pivoted to the guides in the upper ends of these openings are depending latch members 11-11. In each instance a suitable spring 12 is provided 70 for normally maintaining these latch members in closed position against the complementary shoulders 10-10, (see Figure 2).

However when it is desired to remove the 75 lines from said guides 9-9 these latch members may be swung inwardly in obvious manner.

Arranged horizontally between the sides of the latch member and adjacent the lower end are pins 13-13 each of which carries 80 a loose line supporting roller 14. Obviously the lines, one of which is illustrated in Figure 1 and designated by the reference character C are arranged through the guide members 9-9 and in flat position upon the rollers 14-14 so as to support the lines and to 85 facilitate the movement of the same by the driver of the implement.

It will thus be seen that I have provided a highly novel, simple, and efficient cultivator line rack that is well adapted for all of the purposes heretofore designated even though I have herein shown and described the invention as consisting of certain detail structural elements, it is nevertheless to be understood that some changes may be made therein without affecting the spirit and scope 90 of the appended claims. 95

Having thus described my invention, what 100 I claim as new is:

1. In a line rack for cultivators wherein the cultivator includes a forwardly extending draw bar, a member adapted to be secured to the bar and to extend vertically thereabove and guide members arranged at the upper end of said first member at opposite sides thereof whereby to receive said reins, each guide member consisting of a loop having an opening therein to facilitate the arrangement of the line into the loop and means normally closing said opening.
  2. In a line rack for cultivators wherein the cultivator includes a forwardly extending draw bar, a member adapted to be secured to the bar and to extend vertically thereabove and guide members arranged at the upper end of said first member at opposite sides thereof whereby to receive said reins, each guide member consisting of a loop having an opening therein to facilitate the arrangement of the line into the loop and means normally closing said opening, and a horizontally arranged loose roller arranged within each loop for the support of the line.
25. In testimony whereof I affix my signature.

BOLDEN S. KELLEY.
